UNITED STATES PATENT OFFICE.

CHARLES G. JOHNSON, OF WILLOW BROOK, SASKATCHEWAN, CANADA.

HAT-PIN-POINT PROTECTOR.

1,098,732.

Specification of Letters Patent. Patented June 2, 1914.

Application filed May 10, 1913. Serial No. 766,831.

To all whom it may concern:

Be it known that I, CHARLES G. JOHNSON, a subject of the King of Great Britain, residing at Willow Brook P. O., in the Province of Saskatchewan, Dominion of Canada, have invented certain new and useful Improvements in Hat-Pin-Point Protectors; and I do hereby declare the following to be a full, clear, and exact description of the invention, such as will enable others skilled in the art to which it appertains to make and use the same.

The present invention is directed to improvements in hat pin point protectors, and has for its object to provide a device of this character which when in place, will not only protect the point, but will prevent accidental displacement of the pin.

A further object of the invention is to construct a device of this character, which is exceedingly simple in construction, effective in operation, and one which is ornamental in appearance.

With these and other objects in view, this invention resides in the novel features of construction, formation, combination and arrangement of parts to be hereinafter more fully described, claimed and illustrated in the accompanying drawings, in which:—

Figure 1 is a side elevation of the device showing the same in place upon a pin, Fig. 2 is an enlarged sectional view through the same, Fig. 3 is a sectional view on the line 3—3 of Fig. 2, Fig. 4 is a similar view on line 4—4 of Fig. 2, Fig. 5 is a similar view on the line 5—5 of Fig. 2, and Fig. 6 is a perspective view of the jaws before being assembled.

Referring to the drawing, the numeral 1 designates a casing, preferably circular in cross section and having one end terminating in a flared mouth 2. Formed upon the other end of the casing 1 is a flange 3, said flange having notches 4 formed in the edge thereof and at diametrically opposite points. The flange is also provided near its edge with slots 5, which are also arranged diametrically opposite. The arms 6 of the jaw member engage the notch 4.

The jaw member 7 is formed from resilient sheet metal, and is so bent as to provide a substantially circular head 8 which is connected to the arms 6 by vertical flanges 9

and gripping jaws 10, which are substantially triangular in cross section and have 55 their opposing edges formed with opposing grooves 11. The jaw member 12 is also formed from a single length of metal and is bent upon itself to form a head 13, which terminates in spaced arms 14, said arms for 60 a certain distance of their length bear against the jaws 10, thus effectively guiding the point of the pin 15 so the same will engage the head 13 of the member 12, thereby limiting the movement thereof. The arms 65 14 engage the slots 5, thereby holding the same in tight engagement with the jaws 10. The inner ends of the arms 6 of the jaw member 7 are engaged by the ring 16 which holds said arms in tight engagement with 70 the casing as clearly shown in Fig. 2 of the drawing. The head 8 of the jaw member 7 is provided with a circular plate 17 and against which bears the bight of the head 13 of the member 12, said bight being 75 secured to the plate 21 in any suitable manner, and at right angles to the head 8 of the jaw member 7. The ring 17 also engages the arms 14 of the member 12, and holds the same in tight engagement with the casing 1. 80 It will be further noted that by passing the arms 6 of the jaw member 7 through the notches of the flange 3 that the same will yield when the pin point is being passed between the gripping jaws 10 and as soon as 85 the movement of the pin is stopped the jaws will grip the same. By providing the arms 14 the pin point will engage the same should it accidentally disengage the grooves 11 of the gripping jaws 10, thus directing the 90 point so that it will positively engage the head 13.

What is claimed is:—

1. A hat pin point protector comprising a casing, a flared mouth formed upon one 95 end of the casing, and a flange upon the other end, a jaw member and a member arranged at right angles to each other, said members having arms engaging said flange, a ring engaging said arms to hold the members in engagement with the casing.

2. A hat pin point protector comprising a casing, a flange formed upon one end thereof, notches formed in the flange, slots also formed in the flange, a jaw member comprising resilient arms, opposed gripping

2
jaws carried by the arms, a second member comprising arms for engaging said jaws of the first-named member to guide the pin point, the arms of the first-named member 5 engaging the notches formed in the flange, while the arms of the second member engage the slots formed in said flange, and a ring slidable on the casing for engaging the arms

of both to hold the same in engagement with the casing.

10

In testimony whereof, I affix my signature, in the presence of two witnesses.

CHARLES G. JOHNSON.
